CLAIM

The ornamental design for scissors, as shown and described.

DESCRIPTION

FIG. 1 is a front perspective view of a first scissor;

FIG. 2 is a front view thereof;

FIG. 3 is a rear view thereof;

FIG. 4 is left side view thereof;

FIG. 5 is right side view thereof;

FIG. 6 is a top view thereof;

FIG. 7 is a bottom view thereof;

FIG. 8 is a rear perspective view thereof;

FIG. 9 is a front perspective view of a second scissor;

FIG. 10 is a front view thereof;

FIG. 11 is a rear view thereof;

FIG. 12 is left side view thereof;

FIG. 13 is right side view thereof;

FIG. 14 is a top view thereof;

FIG. 15 is a bottom view thereof; and,

FIG. 16 is a rear perspective view thereof.

All broken lines represent unclaimed features of the article to which the design is applied.

1 Claim, 12 Drawing Sheets(56)
